METAL-FOLDING MACHINE WITH INTER-CONNECTED FOLDING AND WORK-CLAMPING MEANS

Alphonse A. Espari, New Haven, Conn.

Application November 8, 1946, Serial No. 708,493

6 Claims. (Cl. 153—16)

1

This invention relates to metal-folding machines, and more particularly to those of the hand-operated type operable by means such as a hand crank, which are suitable for bending up the edges of sheet metal plates for the purpose of flanging them. Such machines are commonly known as bar folders, and they comprise in their construction a stationary forming member in the nature of an anvil against which the sheet is clamped preliminary to bending, and over one edge of which the metal is bent by operation of a turning folder bar whose turning movement is imparted by the hand crank.

In machines of this type there has been considerable inconvenience and loss of time involved in the clamping of the work sheet in position prior to the folding operation, and one object of the present invention is to overcome this drawback.

Another object of the invention is to provide a machine having a work-clamping means that is operable from the same manual operating means as the folding bar so as to have a clamping movement preliminary to the folding, and thereby increase the speed with which the machine can be operated and increase the output of the machine.

Another object is to improve the structure and efficacy of machines of this general type.

In the accompanying drawings:

Fig. 1 is a side elevation of a machine embodying my improvements;

Fig. 2 is a top plan view, with certain parts broken away;

Fig. 3 is a view from the side opposite that shown in Fig. 1, the casing of the gears being shown in section;

Fig. 4 is an end view looking from the right-hand end of Fig. 1, the operating shaft section adjacent that end of the machine being shown in section;

Figs. 5, 6 and 7 are, respectively, sections on lines 5—5, 6—6 and 7—7 of Fig. 1;

Fig. 8 is a detail showing one of the end frames;

Fig. 9 is a section on line 9—9 of Fig. 4, this view being a broken view;

Fig. 10 is a transverse section showing parts of the machine as they appear at a certain stage of the folding operation;

Fig. 10^A is a section on line 10^A—10^A of Fig. 10;

Fig. 10^B is an enlarged section on line 10^B—10^B of Fig. 2;

Fig. 11 is a view similar to Fig. 10, showing a later stage of the operation;

Fig. 12 is a section on line 12—12 of Fig. 9;

2

Fig. 13 is a detail of one of the transverse partitions; and

Figs. 14, 15 and 16 are sectional views illustrating different stages in the folding of a metal sheet.

The machine selected for illustration in the drawings is one suitable for the folding of metal sheets that may be as wide as thirty inches, although this dimension is given only by way of example, and the machine is elongated in the direction of the width of the sheet, having an operating hand crank at one end. It comprises a frame in which is arranged for turning movement on a longitudinal horizontal axis a folding bar, said bar in operation being swingable from a substantially horizontal position at one side of the frame into different positions in which it cooperates with a substantially horizontally disposed anvil member at the opposite side of the frame. The metal sheet to be folded is introduced between the anvil member and the folding bar, the extent of the introduction being controlled by stop members that are conveniently adjustable. There are also provided novel means for clamping the sheet against the anvil preliminary to folding, said means including an upwardly movable clamping bar which is operable from the hand crank or the like that is used to actuate the folding bar. The clamping bar is controlled in its upward and downward movement from the operating means for the folding bar through the use of a cam shaft located beneath the clamping bar. The folding bar in its initial position, preliminary to folding, has its active or folding face spaced downwardly to a certain extent from the folding edge of the anvil member. After the workpiece has been introduced to the required extent into a space immediately beneath the edge portion of the anvil member, the clamping bar is shifted to move it upwardly into firm clamping cooperation with the anvil member, and substantially simultaneously the folder bar is moved up to its operative position with respect to the anvil member.

In the drawings the frame of the machine is indicated generally at 20, the anvil member at 21, the swinging folding bar at 22, the latter being operable by a hand crank 23 located at one end of the frame, and the clamping bar being indicated at 23^A. The cam shaft previously referred to is indicated at 24, the same being located below the clamping bar. For limiting the introduction of the workpiece into a space between the anvil member and the clamping bar, a laterally adjustable gauging slide is employed, the same being

indicated at 25 and being equipped with a number of suitable stop members 26, as hereinafter described. The gauge member 25 is adjustable laterally by a number of adjusting screws 27. The turning axis of the folder bar 22 is located above and in line with the cam shaft 24. The folder bar is mounted between and connected to shaft sections 28 and 29, best shown in Fig. 9, of which the section 28 is connected to the crank member 23. Between the shaft section 28 and the cam shaft 24 is a gear connection, indicated generally at 30, and including gears covered by a gear casing 31. There are also cam connections between the cam shaft 24 and the shaft sections 28 and 29, as hereinafter described.

Referring now to the details, the frame 20 has a bottom member 32 which extends throughout its length and is turned up at one end to provide an integral end wall 33 having at the upper part thereof an upwardly elongated hole or slot 34 accommodating a portion of shaft section 28, as shown in Fig. 9. The inner end portion of the crank member 23 has a hub 35 which is applied over the outwardly extending end portion of shaft section 28 and suitably fixed thereto. At the opposite end of the frame the latter is provided with an inset end wall member 36 suitably fastened to the bottom plate. At the side of the frame which is located away from the folder bar, the frame is closed in by a side wall member 37, which is suitably fastened in place, said member in this particular case being set in under the butt end of the anvil 21 and suitably secured thereto, and thus acting as a partial support for the anvil. The adjusting screws 27, previously mentioned, are mounted in the member 37 so as to be rotatable therein. At the opposite side of the frame the latter is left open, so that the folder bar will have no interference with its movements. The side wall member 37 does not extend throughout the length of the frame, but, on the other hand, extends from the end wall 36 to a transverse wall member 38. The wall member 38 is near the end wall 33, and between them the gearing 30, previously mentioned, is accommodated, also the gear casing 31.

The end wall 36 serves as a mounting for the shaft section 29, and has at the upper part thereof a recessed portion 39 receiving a bearing 40 for said shaft section, said bearing being movable upwardly in the recessed portion or notch 39 of the wall, and being limited in its upward movement by an adjusting screw 41 threaded in a member 42 bridging recess 39. By mounting it in this manner, the shaft section 29, normally resting in a recess in the wall 36, can have a limited upward movement. Similarly the shaft section 28 has a mounting in the transverse wall 38 whereby it can be moved upwardly to a limited extent. For this purpose the bearing 43, embracing shaft section 28, is adapted to move upwardly in a recess 44 in wall 38, and is adapted to make contact with an adjustable screw 45 mounted in a bridge member 46.

The cam shaft 24 has a bearing at one end in the end wall 36, and near the opposite end of the cam shaft is another bearing provided in the wall 38. In the form shown these bearings are created by providing suitable bores in the walls 36 and 38. The cam shaft is also supported at a number of points between its ends, and in the present case this shaft is supported by members 47 that can be referred to as partition members set in the frame, which partition members also serve to support some of the other

operating parts, as hereinafter described. In addition to the partition members just referred to, the cam shaft is also supported at intervals by blocks 48 set in under the shaft and supporting it from beneath. In Fig. 3 the general arrangement of these partition members and blocks is disclosed, and it will be noted that in this case there are six partition members 47 and six blocks 48. Each of the blocks 48 rests at its lower end on the bottom of the frame and is notched at its upper part, as shown at 49, to receive a portion of the shaft. Each of the partition members 47 rests at its lower end on the bottom of the frame, and has one of its side edges supporting the side wall 37 of the frame. In each of these partitions is a hole 50 through which extends a portion of the cam shaft. The cams 51, provided on the cam shaft 24 for the purpose of providing for upward movement of the clamping bar 23^a, may be six in number, each cam being located adjacent a supporting block 48. The cams 51 may be separate members slipped over the shaft 24 and then fixed thereto by suitable means such as pins 52. Each of these cams preferably has a periphery which, through the greater part thereof, is concentric with the shaft but is cut away to form a recess 53, as shown in Fig. 6. This recess is adapted to be engaged by a downward projection on the clamping bar 23^a. In the form shown the projection is provided by mounting on the clamping bar a vertically adjustable screw 54 having a lower end shaped as a rounded nose 55. Each screw is adjustable vertically in a threaded socket 56 suitably fastened to one side of the clamping bar. The screw is adjusted so that its lower end projects to the desired degree beyond the lower surface of the clamping bar, and the screw is then fixed in the adjusted position by a set screw 57.

Each of the partitions 47 is provided above hole 50 with a notch 58 having upright side edges and providing a recess in which a portion of the clamping bar 23^a is received, and by means of which the clamping bar is guided in a vertical direction. Normally the lower edge of the clamping bar rests on the bottom of the recess 58, but by actuation of the adjacent cam 51 the clamping bar can be raised, as shown in Fig. 10.

The upper edge portions 59 of the partitions 47, shown in Fig. 13, serve as supports for a superposed member, which in turn supports the gauge bar 25. There are several such superposed members, each supporting the gauge bar throughout a portion of its length, and in this particular case the superposed members referred to are indicated at 60, as shown in Fig. 2. Such a member 60 may be supported at the respective ends on two of the adjacent partitions. Certain of the partitions 47 can be placed so that they are at a short distance from each other, thus providing two relatively narrow spaces in the frame, in which spaces the shanks of the screws 27 are accommodated, there being in this instance two of these screws. The superposed members 60, previously referred to, are arranged to extend between and bridge partition members which are farther apart than those between which the screws 27 are located. The members 60 provide an ample support for the gauge bar 25 which extends substantially throughout the length of the frame. The screws 27 may have round knurled heads and each screw may have a bearing in the wall 37 provided between a shoulder 27^a provided on the head and a collar 61 pinned

to the shank of the screw. The shank of the screw is threaded, as shown at 62, and the threaded portion engages a threaded bore provided in a block 63, which is fixedly secured in an appropriate manner to the gauge bar and extends downwardly from the gauge bar. By this arrangement the gauge bar is moved in opposite directions laterally of the frame when the screw is rotated in the respective directions, the gauge bar in this movement being guided upon the upper faces of the supporting members 60. The stops 26, previously mentioned, are provided upon the gauge bar at the inner edge of the gauge bar, and each of these stops may be in the form of a U-shaped member held in place by a screw 64 screwed into the gauge bar. The U-shaped stops are provided with free ends 65 that project into notches 66 cut into the clamping bar 23^a from the upper edge thereof. The notches 66 extend entirely across the upper edge of the clamping bar 23^a, and the legs of the U-shaped stop members project into these notches to a greater or less extent, depending upon the position to which the gauge bar 25 is adjusted. After the gauge bar has been adjusted laterally by means of the screws 21, it can be firmly fixed in position by suitable means, for example, by means of screws 67 passing loosely through the wall 37 and threaded so as to have threaded engagement with the gauge bar. These screws are each equipped with a locking nut 68 bearing against the outer surface of wall 37.

The folder bar 22 is preferably of composite construction, the same being in the form of a truss for giving it greater strength. For this purpose the folder bar comprises the bar proper 69, which is a straight member, and the angular truss member 70 having its intermediate portion spaced from the intermediate portion of bar 69 by means of a bolt 71. The folder bar is applied at its respective ends to round disk members 72 and 73, respectively, the first of which is suitably fixed to the inner end of shaft section 28 and the second of which is similarly fixed to the shaft section 29. These disk members are disposed at the inner faces of the walls 38 and 36, respectively, and overlie the bearings 43 and 44, respectively, and the bridge members 46 and 42, respectively. Engaged with the peripheries of the respective disks 72, 73 are disks 74 and 75, respectively, pinned to the cam shaft 24. There is a certain cam action between the disks of each pair 72, 74 and 73, 75, for the purpose of raising the longitudinal axis of the folder bar, and in the present instance this cam action is produced by deforming the lower disks 74 and 75, which, as shewn in Fig. 7, are each provided at one point in the periphery with a depression or dwell 76 adapted to accommodate a portion of the periphery of the cooperating disk, and conforming in shape to such portion.

The folder bar 22 is suitably attached to the upper disks 72 and 73 as by means of screws passing through the disks and into the ends of bar member 69. Such screws are indicated at 77 in Fig. 7.

The gearing 30, previously mentioned, includes a gear 78 fixed to the shaft section 28, and a gear 79 fixed to the corresponding end of the shaft 24. These are spur gears. The gear 78 is preferably somewhat smaller than the gear 79, as shown in Fig. 5, and gear 78 has on its periphery a portion 80 which is devoid of teeth and is flattened off, as shown in Fig. 5, so as to be able to rest upon the teeth of gear 79 when

the shaft section 28 is in the position shown in Fig. 9. When gear 78 is in the position shown in Fig. 5, the teeth of the gear which are at opposite sides of the portion 80 are in close proximity to the teeth of the gear 79.

For the purpose of providing adjustable means for limiting the swing of the folder bar, an adjustable stop may be placed on end wall 33. A stop member may be provided in the form of an arcuate slotted piece 81 held in adjusted position by bolts 82 engaging the wall 33, said arcuate piece having at one end a projecting stop member 83 adapted to be contacted by the hand crank 23. Preferably the hand crank is substantially horizontal when the folder bar is in the position shown in Fig. 6, and by adjustment of the stop member the upward swing of the folder bar relatively to the anvil can be limited as desired.

For the purpose of providing an indication at the upper part of the frame of the lateral position of the gauge bar 25, suitable indicating means may be employed. In the form shown, the gauge bar is provided at two points in its length with upstanding headed members 84 having cylindrical heads projecting upwardly into transverse slots 85 provided in the anvil, the sides of said slots having associated therewith suitable scales adapted to register with markings on the headed members 84.

In the operation of the machine, the gauge bar 25 is first adjusted by the adjusting means above described so as to permit the metal sheet to be operated upon to be inserted to the desired extent between the upper edge of the clamping bar 23^a and the opposing lower face portion of the anvil 21. In Fig. 6, for example, the gauge bar is shown in full lines in one position, and in dotted lines in another position. The anvil at its upper portion is provided with an inclined surface that leads to a thin inner edge. After the metal sheet has been inserted into the bite between the parts above mentioned, so that the inner edge of the sheet engages the stops 26, the bending or folding operation is commenced by turning the crank in a counter-clockwise direction with reference to Fig. 14, and with reference to Figs. 5 and 6. At the commencement of the turning movement, a tooth on gear 78 engages the adjacent tooth of gear 79, thus starting the rotation of gear 79 in the direction indicated by the arrow in Fig. 5. As the rotation continues the cams 51 act to raise the clamping bar 23^a, which is thereby moved upwardly to clamp a portion of the sheet against the anvil. The screw pins 54 are, of course, adjusted lengthwise beforehand, so that when the cylindrical surfaces of the cams are in engagement with the lower ends of the pins, the plate will be firmly clamped against the lower surface of the anvil with the required amount of pressure for holding the plate against dislocation as the folding proceeds. In this operation the teeth of the gear 78 engage teeth at the upper part of gear 79, and the dwells 76 of the lower cam disks 74, 75 are shifted so that the cylindrical surfaces of these cam disks engage the peripheries of the upper disks 72, 73. This latter action has the effect of raising and slightly swinging the folder bar, and the latter is moved upwardly so that before any considerable folding action takes place the upper left-hand-corner of the folder bar (Fig. 14) is brought substantially to the plane of the lower surface of the anvil, with said corner in close proximity

to the edge of the anvil. After the folder bar has reached this position where the turning axis of the folder bar (and of the shaft sections 28 and 29) is substantially coincident with the inner edge of the anvil, the swing of the folder bar continues, as shown in Fig. 15, thus bending the metal sheet to form a flange at the margin of the sheet. In the case illustrated in Fig. 16, the body of the sheet is folded down against the inclined upper surface of the anvil, but the extent of the fold will, of course, depend upon the adjustment of the stop member 81.

It will be obvious from the foregoing description that, after a folding movement, such as shown in Fig. 16, for example, has been accomplished, a reverse rotation of the folding shaft comprising the sections 28 and 29 will permit the workpiece to be released, the clamping bar and the folding bar being restored to the initial positions.

It will be seen from the foregoing that the machine can be operated very conveniently and very quickly, no separate operating means for the clamping bar being required, and the clamping operation, as well as the folding operation, being accomplished by one hand of the operator, leaving his other hand free for other purposes. On the first movement of the machine, the work which has been inserted under the edge of the anvil is automatically clamped by the rise of the clamping bar, and as the clamping bar is rising the folder bar is being moved or translated upwardly from a lower position to a position in which one of its corners, adjacent the axis of rotation, is raised to operative position with respect to the anvil. Then the folder bar is actuated on continued movement of the operating means so as to create the fold. By the provision of these features the operation of the machine is much more rapid than heretofore, and production is speeded up considerably. Moreover, the machine is of simple and durable structure.

It will be apparent that in the machine disclosed the anvil has a flat lower face leading to a pointed folding edge, and that the clamping bar is adapted to clamp the work against the lower face over an area that ends approximately at the folding edge. It will also be apparent that the folder bar has a folding face which is initially in a lower position but at a later stage swings on an axis substantially coincident with the folding edge of the anvil.

In the drawings a preferred form of the machine is illustrated, and it is to be understood that this is by way of example only, and that various modifications in the organization and changes in the details may be made without departing from the principles of the invention or the scope of the claims.

What I claim is:

1. In a metal-folding machine, the combination of a fixed anvil, a frame in which the anvil is mounted, a work-clamping bar beneath the anvil slidable vertically upwardly to clamp the work against the anvil, a rotary shaft having fixed bearings in the frame and carrying cams which upon rotation engage the work-clamping bar to lift it into the operative position, a folder bar structure embodying a folder bar swingable with respect to the anvil to fold the workpiece and also embodying rotary shaft sections having mountings in the frame which permit the lifting of said sections in a vertical plane, and means of operative connection between said folder bar

5 structure and said cam shaft including gears and cams arranged so that upon rotation of the folder bar the cam shaft is rotated and the folder bar lifted.

2. A metal-folding machine as defined in claim 1, in which the cams in said means of connection are located internally of cross members provided in the frame and the gears are located externally of one of said cross members.

3. In a metal-folding machine, the combination of a fixed anvil, a frame in the upper part of which said anvil is mounted, said frame having a bottom member, end members, and a plurality of cross members in the nature of partitions, a work-clamping bar slidable vertically in the partitions and adapted to clamp the work against the lower surface of the anvil, a rotary shaft mounted in the frame beneath the work-clamping bar carrying a plurality of rotary cams adapted to move the clamping bar upwardly, a folder bar structure embodying a folder bar swingable with respect to the anvil to fold the workpiece and also embodying shaft sections adapted to move vertically in the upper part of the frame, said folder bar having an inoperative position in which its active face is spaced downwardly from the level of the under face of the anvil, and operative means of connection between said bar structure and said cam shaft

20 whereby upon swinging movement of the folder bar the cam shaft is rotated and the folder bar lifted bodily.

4. In a metal-folding machine, the combination of a fixed anvil, a frame in the upper part of which said anvil is mounted, said frame having a bottom member, end members, and a plurality of cross members in the nature of partitions, a work-clamping bar slidable vertically in the partitions and adapted to clamp the work against the lower surface of the anvil, a rotary shaft mounted in the frame beneath the work-clamping bar carrying a plurality of rotary cams adapted to move the clamping bar upwardly, a folder bar structure embodying a folder bar swingable with respect to the anvil to fold the workpiece and also embodying shaft sections adapted to move vertically in the upper part of the frame, and operative means of connection between said bar structure and said cam shaft whereby upon swinging movement of the folder bar the cam shaft is rotated and the folder bar lifted, said means including co-acting gears one of which is mutilated, one of said gears being mounted on the cam shaft and the other upon one of said shaft sections.

5. A metal-folding machine as defined in claim 4, in which one of the gears is mounted on one end of said cam shaft and in which said means of connection also includes pairs of camming disks located adjacent the ends of the folder bar.

6. A metal-folding machine as defined in claim 5, in which said cam shaft is supported within said partition members and is also supported by additional members in the spaces between the partition members and in which the clamping bar is slidable in slots provided in the upper portions of said partition members.

ALPHONSE A. ESPARI.
